UNITED STATES PATENT OFFICE.

THADDEUS F. BAILY, OF ALLIANCE, OHIO.

ELECTRODE CONTROL FOR ARC FURNACES.

Application filed May 24, 1926. Serial No. 111,437.

In the present types of automatic arc furnace control apparatus, such as are in common use, the movement of the electrode is accomplished by a motor which in turn is controlled by some current control device operating relays which in turn control the movement of the motor and hence the electrode.

The disadvantage of the aforementioned type of control is that an appreciable delay elapses between the time overload or underload condition is developed in the furnace and the time that the corrective measures are applied.

The object of the present type of equipment is to provide a means that is almost instantaneous or selectively, timed in its action for correcting any variation in the power in-put to the furnace and this is accomplished by placing a powerful magnet directly onto the mast mechanism or electrode holder to which one of the electrodes is attached. It will further be noted that while this magnet has a limited range sufficient, however, to take care of any normal fluctuations in the current, the equipment described is provided with means for taking care of any required variations by means of an automatic switch which is operated by the movement of the mast or holder on which the magnet armature is attached, so that when the magnet, in controlling the current has reached nearly its extreme travel in either direction beyond which it is no longer fully able to control the current supplied to the electrode, it will operate a reversible switch, controlling the motor for operating the entire mast arm mechanism raising the outer sleeve of the electrode mast end on which the magnet stator is rigidly attached, thus again bringing the main electrode mast into its central position.

It will further be noted that in one arrangement of the present invention, the electrode mast proper is floated at its upper end on a spring, the lower end of which rests on the electrode mast sleeve before mentioned, the weight of the mast mechanism proper and electrodes normally depressing this spring so that the armature of the magnet is in its highest position when the maximum amount of current is flowing to the coils of the magnet. The armature is thus pulled down depressing the spring until current flows from electrode to electrode, and,

if more power than is desired flows between electrodes, then the current flowing to the magnet coils is decreased and the strength of the magnet pull lessened until the spring has pulled the electrode sufficiently far apart to maintain the correct current flow.

The amount of current flowing to the coil of the magnet is controlled by means of a reactor coil composed of a loop of transformer steel laminæ around which is wound a coil of insulated copper wire of the proper number of turns and cross-section and also one of the leads going to the electrodes is passed through these laminæ to produce a dampening effect in the current.

One of the terminals of this coil is connected to the electrode and the other one goes to one terminal of the magnet coil. The other end of the magnet coil is then led to the other electrode.

An embodiment of the invention is illustrated in the accompanying drawing, in which

The figure is a diagrammatic view of an arc furnace provided with the improved control apparatus.

Similar numerals refer to similar parts throughout the drawing.

The furnace is indicated generally at 1, and provided with the lower electrode 2, which may be stationary, and is connected by the cable 3 to any suitable source of electric power. A removable lid, or cover, 4 may be provided for the furnace, having the central opening 5, through which the movable electrode 6 is extended, said electrode being connected by the cable 7 to the same source of electric power.

The movable electrode may be suspended from the arm 8, supported at the upper end of the longitudinally movable mast or electrode support 9, which may be slidably movable within the tube 10 also slidably mounted within the bearing 11 carried at one side of the furnace.

The lower end of the tube 10 may be enlarged, as at 12, forming a casing for the magnet coil 13 connected as by the wires 14 and 15 to the cables 3 and 7 respectively. The wire 14 is preferably connected to a coil 16 wound around the laminated iron core 17 of a reactor, the cable 3 being extended through the hollow center of said core.

The armature 18 is carried by the mast 110

9 and extended through the coil or stator 13 of the magnet and a coil spring 19 is connected to the upper end of the mast, and interposed between the same and the upper end of the sliding tube 10, and is arranged to work against the pull of the magnet to tend to raise the mast 9, and with it the electrode 6, while the magnet tends to lower the same.

10 The magnet coil, or stator, and tube 10 are arranged to be longitudinally moved within the guide 11 as by the cables 20 and drums 21. Each of these drums may be provided with a worm gear 22 engaged by 15 a worm 23, upon the shaft 24 of the reversing motor 25.

In the drawing a three phase motor is illustrated although it will be understood that this is not essential. Current is supplied to this motor through the wires 26 leading from any suitable source of electric power, such as indicated at 27, a reversible switch 28 being located in the motor circuit and being provided with a handle 29, engaged by a loop 30 upon the mast 9 or armature 18, whereby movement of the mast relative to the tube 10 will cause the switch 28 to be operated, it being understood that this switch is carried by, or fixed with relation to, 10 the tube 10 and magnet coil 13.

In starting the operation of this control equipment with the electrodes so far apart that the pull of the magnet may not be such as to draw an arc between the electrodes, the armature 18 of the magnet will be so far depressed as to throw the automatic reversible switch 28 into its lower position, therefore making contact with the electrode moving motor 25 so that the entire mast 9 and tube 10 descends until an arc is established between electrodes.

The instant that this arc is established the current flowing to the magnet coils 13 is reduced, due to the bucking effect of the rushing current through the main leads affecting the windings on the reactor coil 17, and since the pulling effect of the magnet is therefore reduced the spring 19 is able to raise the mast 9 and upper electrode a sufficient distance, under normal conditions, to steady the arc.

However, under abnormal conditions, if this upward movement caused by the magnet is not sufficient to fully control the current, the armature of the magnet having reached its upper position it throws the motor control switch in the reverse position, to that previously mentioned, and the motor for operating the mast mechanism raises the entire mast until the current flowing in the main arc circuit has become normal.

During this upward movement the magnet armature is adjusting itself with reference to the magnet coils and when the normal relation of these two is effected their

relative position is such as to put the motor control switch in its neutral position and stop the motor.

I do not wish to be limited to the shunt arrangement shown in the drawing, as this 70 may be a series connection or a combination of shunt and series connection, for connecting the magnet with the electrodes; and also I wish to have it understood that the electrode may be controlled by a counterweight 75 or partly by a counterweight and partly by the spring.

The magnet performs two duties, that is by pulling apart the electrodes it builds the 80 arc distance and by its especially shaped armature and stator acts like a reactor of full iron core, therefore balancing and maintaining a steady even current flow.

I claim:

1. An electrode control for arc furnaces 85 including a longitudinally movable electrode support, means for moving said support longitudinally, a motor controlling said moving means and a magnet operatively connected to the support for controlling the 90 closer regulation of the support.

2. An electrode control for arc furnaces including a longitudinally movable electrode support, means for moving said support longitudinally, a motor controlling said moving means and a magnet operatively connected to the support for controlling the 95 closer regulation of the support and the movement of the support controlling the 100 operation of the motor.

3. An electrode control for arc furnaces including a longitudinally movable tube, a magnet stator carried thereby, a mast longitudinally movable within said tube, a magnet armature carried by the mast and co-operating with the stator, an electrode supported by the mast, means for normally urging the mast upward in the tube, a reversing motor for longitudinally moving the magnet stator and tube and means controlled by 105 the movement of the mast for controlling the movement of the motor.

4. An electrode control for arc furnaces including a longitudinally movable tube, a magnet stator carried thereby, a mast longitudinally movable within said tube, a magnet armature carried by the mast and co-operating with the stator, an electrode supported by the mast, spring means for normally urging the mast upward in the tube, 110 a reversing motor for longitudinally moving the magnet stator and tube and means controlled by the movement of the mast for controlling the movement of the motor.

5. An electrode control for arc furnaces 115 including a longitudinally movable mast, an electrode carried thereby, a motor for longitudinally moving the mast, an electro-magnet for moving the mast independently of 120 the motor, the movement of the motor be- 125

ing controlled by the movement of the magnet armature.

6. An electrode control for arc furnaces including a movable electrode support, an electrode carried thereby, a motor for moving the support, an electro-magnet for moving the support independently of the motor, the movement of the motor being controlled by the magnet.
- 10 7. An electrode control for arc furnaces including a movable electrode support, an electrode carried thereby, a motor for moving the support, an electro-magnet for moving the support independently of the motor, the movement of the motor being controlled by the movement of the magnet.
8. An electrode control for arc furnaces including a movable electrode support, an electrode carried thereby, a motor for moving the support, an electro-magnet for moving the support independently of the motor, the movement of the motor being controlled by the movement of the magnet armature.
- 20 9. An electrode control for arc furnaces including a movable electrode support, a magnet operatively associated with the support and arranged to move the support with-
- 5 10. An electrode control for arc furnaces including a movable electrode support, a magnet operatively associated with the support and arranged to move the support beyond the limit of movement by the magnet.
- 35 11. An electrode control for arc furnaces including a movable electrode support, a magnet operatively associated with the support and arranged to move the support with- 40
- in predetermined limits and a motor operatively associated with the support and arranged to move the support beyond the limit of movement by the magnet, the operation of the motor being controlled by the magnet.
- 45 12. An electrode control for arc furnaces including a movable electrode support, a magnet operatively associated with the support and arranged to move the support with- 50
- in predetermined limits and a motor operatively associated with the support and arranged to move the support beyond the limit of movement by the magnet, the operation of the motor being controlled by the movement of the support.

In testimony that I claim the above, I have hereunto subscribed my name.

THADDEUS F. BAILY.
